UNITED STATES PATENT OFFICE.

EDWARD FELSBERG, OF MONTGOMERY, PENNSYLVANIA.

MANUFACTURE OF LEATHER-LOOP FASTENINGS.

SPECIFICATION forming part of Letters Patent No. 355,068, dated December 28, 1886.

Application filed May 26, 1886. Serial No. 203,333. (No specimens.)

To all whom it may concern:

Be it known that I, EDWARD FELSBERG, a citizen of the United States, residing at Montgomery, in the county of Lycoming, State of Pennsylvania, have invented certain new and useful Improvements in the Manufacture of Leather Loop-Fastenings, of which the following is a specification, reference being had therein to the accompanying drawings.

10 This invention relates to improvements in devices for securing strap-loops to harness; and it consists in providing a fastener having attaching-prongs formed of sheet-metal blanks, all as will be hereinafter fully explained, and 15 particularly pointed out in the appended claim.

The annexed drawings, to which reference is made, fully illustrate my invention, in which—

20 Figure 1 represents face view of a fastener attached to a leather loop. Fig. 2 is a vertical sectional view of the same. Fig. 3 is a view of the fastener in the second blank form. Fig. 4 is a face view of the loop, the fastener removed. Fig. 5 is a perspective view of the 25 fastener, and Fig. 6 is a plan view of the same as the blanks appear in the sheet metal before they are separated.

Referring by letter to the accompanying 30 drawings, A designates the fastener, which consists of the broad body portion *a* and prongs *b*, which are bent at right angles to said body-plate before being finally clinched to the loop.

B. The ends *c* of this loop are provided with 35 slits *d*, to receive said prongs, and are firmly held together after the fastener is inserted and clinched, as shown in Fig. 2 of the drawings.

It will be seen that the fastener is easily attached to the loop or detached therefrom, and

serves to hold the loop or the ends thereof 40 firmly together, thus dispensing with stitching the same, as heretofore, and any number of the fasteners can be "struck up" out of sheet metal at one time, as indicated in Fig. 6, without waste of material. At the same time said 45 fasteners can be silver, nickel, or gold plated or japaned, thus making them ornamental, as well as serving as a strong holder for the ends of the loop, which may be stationary or slide. 50

By reference to Fig. 6, which shows the rows of blanks as they are cut in the sheet, it will be seen that the prongs *b* of one transverse row are equal in width and length to the spaces between the prongs *b* of the adjacent series, 55 the body portions *a* being all of a uniform size.

I am aware that it is not new to produce a sheet-metal fastener formed entire and having prongs adapted to unite the ends of leather belting, and I disclaim such devices, broadly 60 considered.

Having described my invention, what I claim, and desire to secure by Letters Patent, is—

The improvement in the art of manufacturing fasteners, which consists in striking out 65 from a sheet of metal longitudinal strips having lateral prongs, forming a series of H-shaped blanks, as shown, then separating said strips transversely into single fasteners, and bending 70 the prongs at right angles to the body of the same.

In testimony whereof I affix my signature in presence of two witnesses.

EDWARD FELSBERG.
